JAMES WILLIAMS AND AGUR JUDSON, OF NEWARK, NEW JERSEY, ASSIGNEES
TO ALBERT EDWARD RIDLEY AND ARTHUR JOHN RIDLEY, BOTH OF
NEW YORK, N. Y.

SAFETY POCKET ATTACHMENT.

SPECIFICATION forming part of Letters Patent No. 362,913, dated May 10, 1887.

Application filed January 6, 1886. Serial No. 187,804. (No model.)

To all whom it may concern:

Be it known that we, JAMES WILLIAMS and AGUR JUDSON, both of the city of Newark, county of Essex, and State of New Jersey, have invented certain new and useful Improvements in Attachable or Adjustable Pockets for Garments, of which the following is a full, clear, and exact description, reference being had to the accompanying drawings, which form 5 to a part thereof.

The object of our invention is to provide an adjustable attachment for pockets, whereby a pocket made of leather or any other suitable fabric may be readily and securely attached to 15 any part of a garment, either inside or outside, and thus provide a receptacle on any part of the person for holding and carrying money or other valuables.

When money or other valuables are put in 20 the ordinary pocket of a garment, they are usually liable to be extracted by pickpockets or thieves.

Our invention provides a secure receptacle 25 for money or valuables, that can be easily attached to any part of a garment that may be considered most safe or convenient, and detached without any injury to the fabric of the garment.

Our invention consists of a flat metallic eas- 30 ing in which there is provided a revolving bar, on which or to which there is attached a series of curved hooks, and a spring-catch for holding the hooks securely in the cloth.

In the drawings, Figure 1 represents a side 35 section of the metal case, the revolving bar, spiral spring, and catch. Fig. 2 represents an end sectional view of the metal case and pocket attached, with the hooks out of the cloth. Fig. 3 shows an end view of the pocket and 40 attachment when adjusted to a garment. Fig. 4 shows the revolving bar and the curved hooks attached. Fig. 5 represents the outside of the case, with the adjustable knob and slot in which it operates.

45 Referring to the accompanying drawings, A represents one of the sides and the ends of the metallic case.

R is a revolving arm or rod, which works in bearings C C. To this arm there is affixed a

series of sharp curved hooks, E E, the points 50 of which are adapted to fit into a series of holes, D D D, in the casing, and are thus protected when the pocket is attached to or detached from the garment.

F is a spring-catch which serves to keep the 55 revolving arms and hooks securely in their place by holding of a small flange, G, on one end of rod R on the end of the arm.

H is an adjustable screw or knob attached to the spring-catch F, and working in a slot on the 60 outside of the case, as shown in Fig. 5. The lower end of the metallic casing contains a series of small holes, III, by means of which the pocket can be sewed or otherwise attached to the casing.

When it is desired to adjust or affix the 65 pocket to a garment, the catch F is pushed back by means of the knob H, and the flange or handle of the revolving arm is pushed outward, thus lifting the hooks into a horizontal position 70 and nearly at right angles to the casing. The hooks are then inserted in the garment and the flange or handle pulled back into its place over the spring-catch. The spring-catch can then be made rigid by screwing the adjustable 75 knob tight to the casing. It then becomes impossible to remove the pocket without breaking the hooks or tearing away a part of the garment.

Having thus described our invention, what 80 we claim, and desire to secure, is—

In an adjustable pocket attachment, the 85 combination of a revolving bar in a metallic casing, having hooks attached, adapted to engage the cloth of a garment, and provided with a terminal arm bent at right angles thereto, and a spring-catch to engage the arm and hold the hooks in the garment, and provided with a set-screw for holding the spring-catch in a fixed position, substantially as described. 90

In witness whereof we have hereunto signed our names in presence of two witnesses.

JAS. WILLIAMS.
AGUR JUDSON.
